UNITED STATES PATENT OFFICE.

CHARLES F. TAYLOR, OF SPRINGFIELD, MASSACHUSETTS.

PROCESS OF AND APPARATUS FOR TREATING RAGS FOR PAPER-STOCK.

SPECIFICATION forming part of Letters Patent No. 286,503, dated October 9, 1883.

Application filed March 17, 1883. (No model.)

To all whom it may concern:

Be it known that I, CHARLES F. TAYLOR, of Springfield, in the county of Hampden and State of Massachusetts, have invented new and useful Improvements in Processes of and Apparatus for Feeding, Cutting, Dressing, Cleaning, and Treating Rags for Paper Manufacture, of which the following is a specification.

10 Heretofore rags for paper-stock have been stripped—*i. e.*, cut or torn into strips—by hand. This method of stripping is objectionable, because slow and expensive. Cross-cutting—*i. e.*, cutting the strips into small 15 pieces—has heretofore been accomplished both by hand and by machinery, the cross-cutting for the finer grades of paper being done by hand and for the coarser grades by machinery. The machinery heretofore used, however, has not been adapted to cut the materials with a sufficient degree of regularity, and after being cut the stock has not been reduced to the uniform size which is most desirable in the various manipulations to which 20 it is afterward subjected, and the present construction of these cross-cutting machines is such that, however carefully they may be operated, a product of uniform size cannot be obtained therefrom. Attempts have been 25 made to strip and cross-cut without an intermediate handling by connecting two machines. With this arrangement, however, it has been necessary to reduce the rags first by hand to a size adapted for the machine, and no positive 30 means of conveying the strips from one cutter to the other has been provided; but the material has been deposited upon an apron, and conveyed by it to a chute through which they pass, and are deposited upon a second 35 apron, which conveys them to the second cutter. The manner in which the rags are thus presented to the second cutter depends upon chance, and they are as liable to be cut in one direction as another. This defect is found in 40 every machine heretofore made—*i. e.*, it has been necessary to first prepare the rags by hand cutting or stripping for the machine, and the feed has not been positive and has 45 not been within the control of the operator, either as to the manner of presenting the ma-

terial to the cutting device, or as to regulating the size to which the material is cut.

The object of my invention is to provide a means for and a method of stripping rags by machinery; and, further, to obtain, by machinery, a product of a uniform or approximately uniform size; and, further, to provide a machine which shall both strip and cross-cut the stock at one operation—that is to say, with but one handling; and, further, to provide a means of removing foreign matter from the rags at the same handling as when cut, and, further, to accomplish the results desired, as hereinafter set out.

My invention consists in the method or process of treating the rags whereby the desired result is attained, and in the steps requisite to perform the several operations.

It further consists in the feeding mechanism.

It further consists in the means adapted to produce the desired result; and, further, it consists in the construction and arrangement of the parts whereby the objects of my invention are attained.

In the accompanying drawings, in which similar letters of reference indicate like parts, a machine is illustrated which is adapted to perform the several operations.

Figure 1 is a side view of the machine with the pulleys and gears removed, disclosing the portions of the machine which operate upon the rags. Fig. 2 is a sectional view of the same. Fig. 3 is a plan or top view. Figs. 4, 5, and 6 are detail views of the rotary cutters. Fig. 7 is a sectional view of the sieve. Fig. 8 is a top view of the sectional beater-bars. Fig. 9 is a side view of the feeding device, with parts in section, and Figs. 10, 11, 12, 13, and 14 are detail views of the parts of the feeding-device. *i i* represent pressure-rolls, which are also adapted to act as feed-rolls.

a represents a revolving blade, adapted to cut the rags in strips. *b b* represent rotary cutters or shears in gangs, adapted to make a shearing cut. *c* represents a beater adapted to beat or pound the material against the beater-bar *e* as it is fed to it by the feed-roll *d*.

The operation of the machine will be readily understood on referring to the drawings. The

rags being fed upon the apron *m* are carried in the direction indicated by the arrow, and are fed to the pressure-rolls *i*, which are adapted to crush any hard substance. These rolls also 5 act as feed-rolls, holding and feeding the material to the cutter *a*, which, revolving as indicated, carries the material against the fixed knife *t*, thus separating the rags into narrow strips. This operation is termed "stripping." 10 It will readily be seen that by changing the position of the knives—*i. e.*, placing the cutters *b* ahead of the cutters *a*—the stripping will be accomplished by these cutters and the cross-cutting by the cutter *a*. After being cut in 15 strips the rags fall to the apron *f*, which, moving in the direction indicated, carry the rags to the knives *b*, where they are cut in a direction across the cut of the first knife. It will be observed that the first knife cuts the material in a direction parallel with the axis of the revolving knife, and that the strips, falling as cut, are deposited lying in the same direction upon the apron *f*, and are thus by a positive feed carried and delivered to the rotary cutters *b*, where the strips are separated into short 20 pieces.

The size to which the material is cut by the first knife may be varied by varying the feed, or by varying the rapidity of the revolution 30 of the cutter *a*, and the size to which the material is cut by the cutters *b* is varied by varying the distance of separation of the blades. The size to which the stock is reduced may 35 therefore be easily controlled by the operative.

To do away with the objection which might exist of the knives *b* wearing unevenly, I revolve one set a trifle faster than the other, thus distributing the wear over the whole surface of the cutting-faces.

To assist in the feed of the rotary cutters, I corrugate the edge, as shown in Fig. 6, of either one or both sets of cutters.

The beater-bar is made in sections, as shown in Fig. 8, each section *e* being held in position 45 by a spring. Thus, if a thick piece or bunch of cloth pass through and force a portion of the bar from the beater, the other portions are not affected. The sieve has a vibratory motion, and is provided with flails *x*, which lie 50 loosely upon the bottom of the sieve, being held in place by cords *z*, or other like means. The rags, being fed in the sieve at its upper end, pass down the incline between the wire bottom and the flails. The rapid motion of the 55 sieve causes the flails to rise and fall, thus striking the material and pounding out the dust and foreign matter in its passage through the sieve.

The feeding device illustrated in Fig. 9 consists 60 of an endless belt provided with hooks or pins which project from the surface, and when the point of delivery is reached, retreat below the surface, thus completely freeing the rag. The rags are deposited in the hopper, and as 65 the pins pass upward through them they catch the cloth and draw it in the direction of the

moving belt. This construction—*i. e.*, a feed taking from the bottom—is of material advantage in many respects. Clogging is avoided, as the pin, being loaded at the bottom and thus 70 covered, passes through the mass without any addition. The tendency of the mass is to roll from the apron at the top and toward the apron at the bottom. The pressure of the rags in the hopper tends to hold the rag which 75 is being drawn from the mass, thus materially aiding in opening and straightening out the knots and bunches in which the rags are frequently found. A roll, *u*, located at the bottom of the hopper, revolves slowly toward the 80 belt, thus keeping the throat filled.

I construct the pin as shown in Fig. 12, it being pivoted to a frame, which frame is secured to the belt. The position occupied by the pin when out is shown in dotted lines, and 85 when withdrawn in full lines. The rolls *r* are grooved to permit the pins and boxes to pass, as shown in Figs. 10 and 11. The rolls *r* permit the pin to pass, while the roll *r* is grooved only sufficiently to allow the box to pass, the 90 pin being held projecting. It will thus readily be seen that the projecting hooks will catch the rags on their passage through the hopper, and will retain their hold until reaching the roll *r* at the top of the frame, where the pin 95 is permitted to retreat, and the material, being released, is deposited upon a belt or feed-rolls, as may be desired. The belt may be strained on the rolls, but I prefer to secure the links (shown in Fig. 14) to the edges of the 100 belt, and provide spur-wheels at each end of one or more of the rolls, which spurs will engage with the links and move the belt.

Heretofore the blades or cutters for cutting rags have either been made wholly of steel, or 105 were provided with steel facing or cutting-edges. The objection to this construction is that the steel is carried away in fibers or threads. I substitute for steel a cutter made wholly of charcoal-iron chilled. This gives a cutter of 110 sufficient hardness, and the wear or loss is in the form of a very fine powder, leaving a sharp cutting-edge. To increase the capacity of the machine, I arrange a set of cutters at the opposite side of the frame, similar to the 115 first set, and feed to the second cutters on an apron, as indicated in dotted lines.

The feed-rolls may be either smooth or roughened. I prefer to use rolls having roughened or corrugated surfaces, and provide a means 120 to force them together for the purpose of crushing and breaking such foreign matter as may be loosened in this manner.

In this machine I use two sets of cutters of different construction, for the reason that the 125 machinery that would otherwise be required to turn the strips and present them in proper manner to the cross-cutters is avoided. A machine is thus constructed having a direct and positive feed.

By showing various constructions, methods, and features, and failing to claim in this ap- 130

plication all that may be protected by Letters Patent, I do not abandon the same, but intend to make such features the subject-matter of other applications.

5 It will readily be seen that the several operations may be accomplished by separating the operative portions of the machine and causing them to be operated as separate machines, conveying the material by proper 10 means from one device or portion to the other, and that very many modifications may be made without departing from my invention. I do not therefore confine myself to the particular construction shown.

15 Having therefore described my invention, what I claim, and desire to secure by Letters Patent, is—

1. A rag-cutting machine having two sets of cutters, one adapted to cut the rags across the 20 cut of the other, in combination with a means to feed the material to the first set and from the first to the second set.

2. A rag-cutting machine having two sets of cutters, one adapted to cut across the cut 25 of the other, in combination with a positive feed, whereby the rags, after stripping, are conveyed and presented to the second cutters in such manner that the second cut is across the stripping-cut.

30 3. The method of dressing rags for paper-stock by machinery, consisting of first stripping the rags by passing between cutters, then cross-cutting the strips by passing between cutters.

35 4. The method of stripping rags, consisting of passing them through a gang of cutters.

5. In a rag-cutting machine, a gang of rotary cutters or shears adapted to strip the rags, substantially as shown.

40 6. A rag-cutting machine having two sets of cutters, one adapted to strip and the other to cross-cut the rags, in combination with a means to convey the rags from the first to the second cutter without turning the rags in the 45 passage, substantially as shown.

7. A rag-cutting machine having one or more sets of stripping-cutters and one or more sets of cross-cutters, and provided with a means to convey the rags from the strippers to the 50 cross-cutters, substantially as shown.

8. In a rag-cutting machine, a stripping device located above a feed-apron adapted to convey the strips to a cross-cutting device, substantially as shown.

55 9. A cutter, *a*, in combination with cutters *b*, and a means to convey the material from the first to the second cutter, substantially as shown.

10. An improved cutter for cutting rags, 60 constructed of chilled charcoal-iron, substantially as shown.

11. In a rag-cutting machine, two cutters running against each other, one of which runs faster than the other, whereby the wear is evenly distributed.

65 12. In a rag-cutting machine, a rotary cutter having a toothed edge, substantially as shown.

13. In a rag-cutting machine, two sets of cutters, *b*, one or both of which is adapted to move, and is provided with a means to move the faces of one set of cutters against the faces of the other set, substantially as shown.

70 14. A rag-dressing machine having feed-rolls adapted to loosen or crush hard substances, substantially as shown.

15. In a rag-dressing machine, one or more feed-rolls having a roughened or corrugated surface adapted to feed and fold the rags, substantially as shown.

80 16. A feeding device having pins adapted to retreat at the point of delivery, substantially as shown.

17. The method of feeding rags, consisting of drawing them from the bottom of a mass, 85 substantially as and for the reasons stated.

18. A rag-feeding device having an apron provided with links, and having wheels provided with spurs adapted to engage with the links, substantially as shown.

90 19. A rag-feeding device having a hopper provided with a clearer, *v*, and a means to carry the rags from the hopper, substantially as shown.

20. The combination of an endless belt provided with pins adapted to retreat below the surface at the point of delivery, and grooved rolls *v*, and a hopper, all constructed and operating substantially as shown.

95 21. In a rag-dressing machine, a sectional beater-bar having a means to force the sections toward the beater, in combination with a beater and a means to feed the rags to the point where operated upon, substantially as shown.

22. In a rag-cleaning machine, a sieve provided with flails, substantially as shown.

100 23. A rag dressing or cutting machine having rotary cutters whose axes are on approximately the same horizontal plane, whereby the material may be dropped directly to the shearing-edges, substantially as shown.

110 24. In a rag-cutting machine, two sets of rotary cutters, *b*, of large diameter, whereby the shear angle is so reduced that the material will not be forced away from the cutting-edges, 115 substantially as shown.

CHARLES F. TAYLOR.
